UNITED STATES PATENT OFFICE.

GEORGE TIMMERMAN, OF STAUNTON, ILLINOIS.

DEVICE FOR GREASING HOISTING ROPES OR CABLES.

Application filed July 20, 1925. Serial No. 44,789.

To all whom it may concern:

Be it known that I, GEORGE TIMMERMAN, a citizen of the United States, residing at Staunton, in the county of Macoupin and State of Illinois, have invented certain new and useful Improvements in Devices for Greasing Hoisting Ropes or Cables, of which the following is a specification, reference being had therein to the accompanying drawing.

This invention relates to a device for greasing hoisting ropes or cables.

The object of the invention is to provide a device for greasing ropes or cables which may be readily clamped about vertically extending cables without disturbing the cable installation and then supplied with lubricant.

It is also an object of the invention to provide such a device in which hot grease may be utilized to grease the cable and the supply added to while the cable is in motion.

To carry out the above objects I provide a container comprised of two sections hinged together, having an open top and an opening in the bottom and adapted to be tightly clamped together about a cable, the container when so clamped adapted to contain a supply of lubricant to grease the cable passing therethrough.

In the accompanying drawings:—

Fig. 1 is a front elevation of my device clamped about a cable.

Fig. 2 is a top plan view of the device.

Fig. 3 is a prospective view of the device in extended position; and

Fig. 4 is a rear elevation of the device.

In these drawings I have shown the device made up of two sections hinged together and having an open top. Each section comprises a base portion 1, front wall 2, rear wall 3 and end wall 4. The front and rear walls are flush with the front and rear edges of the base while the end walls 4 are spaced from the ends of the base portions, thus leaving a part of the base extending beyond the end walls of the container to provide a firm foundation for the device when it is in operative position about the cable to be greased. The base portion and upright walls of the device may be made of any suitable material, in the present instance wood, said base and walls being secured together by rivets or otherwise as desired. The base and walls are reinforced by metal strips 5, 6 and 7, the strips 5 ex-

tending across the base sections 1 and to points near the top edges of the front and rear walls while the strips 6 and 7 extend from points adjacent the juncture of the rear walls, around the end walls and to points near the joining edges of the front walls, whence they are bent at right angles, as shown at 8 and 9. These right angled portions are provided with apertures 10 and 11 adapted to receive means for clamping the two sections together. In the present instance I have shown screw bolts 12 and wing nuts 13 but any suitable clamping means may be employed which will effectually clamp the sections of the device to prevent loss of lubricant placed in the container thus formed. The two sections of the device are secured together at the rear by hinges 14 whereby the device may readily be placed about a cable already installed, as, for instance, in a mine shaft. The base portion of each section is provided with a semicircular recess which forms an aperture 15 for the passage of a cable 16 when the device is closed and in operative position.

That portion of the base inside the walls of the device is covered with a layer of rubberized fabric 17, which may be held in place in any suitable manner, as by rivets 18. This base covering also has semi-circular recesses which form an aperture 19 for the cable to pass through during the oiling thereof. It will be noted that this aperture 19 is slightly smaller than the aperture 15 and serves as a packing to prevent loss of lubricant during the oiling operation. This base covering 17 as a whole protects the base proper and thus prolongs the life of the device.

Handles 20 are secured to the side walls to facilitate the opening and closing of the device.

When it is desired to install my improved device to oil a cable operating in a shaft, a temporary platform is placed over the shaft allowing space for the cable to pass through. The device is then placed on the platform and clamped about the cable, whereupon grease is poured into the container at the top which is open as shown in the drawing, and the cable lowered through the shaft. It will be seen that in case the container does not hold enough grease for greasing the entire cable, more grease may be readily added while the cable is in motion. This is of particular advantage in an oiling device of this

kind because it permits of the use of hot grease. In cable oiling devices heretofore constructed the containers for the lubricant have been inaccessible for increasing the supply of lubricant while the cable was in motion. A further advantage of the present invention is the hinged feature of the device which permits it to be placed in position about a cable without disturbing the cable itself.

While I have shown and described certain features as constituting my invention, it will be understood that parts have been shown for purposes of illustrations only and that I do not desire to be limited to such details as obvious modifications will occur to a person skilled in the art.

Having thus fully described my invention, what I claim as new and desire to secure by Letters Patent is:—

In a device of the character described, a container comprising sections hinged together having an open top and an opening in the bottom thereof for the passage of a cable, a cover to protect the base of said container and having an opening of smaller diameter than the opening in said base to prevent the escape of lubricant from the container, and means for clamping said sections of the container together, said container when clamped together about a cable adapted to receive a supply of lubricant.

In testimony whereof I affix my signature.

GEORGE TIMMERMANN.
